UNITED STATES PATENT OFFICE.

EARLE R. PIKE, OF PITTSBURGH, PENNSYLVANIA.

MEANS FOR EQUALIZING STRAINS ON CABLES, &c.

1,261,286.

Specification of Letters Patent.

Patented Apr. 2, 1918.

Application filed April 11, 1917. Serial No. 161,307.

To all whom it may concern:

Be it known that I, EARLE R. PIKE, a citizen of the United States, residing at Pittsburgh, in the county of Allegheny and State 5 of Pennsylvania, have invented certain new and useful Improvements in Means for Equalizing Strains on Cables, &c.; and I hereby declare that the following is a full, clear, and exact description thereof, reference being had to the accompanying drawings, which form part of this specification.

This invention is a novel device for equalizing strains on a plurality of ropes, cables or chains used in the mechanic arts for connecting or operating parts; the invention is especially adapted for use with cable operated elevators in which a number of parallel cables are employed, and has particular reference to the means for equalizing the 20 strains on the plurality of cables used to operate the car, and for connecting the car to the counterweight.

I will describe the invention as applied to a six cable equalizer for traction elevators 25 and a description of such embodiment of the invention will enable others skilled in the art to readily adapt and use the same in other connections. The essential features of the invention and combinations of parts 30 for which protection is desired are summarized in the claims.

In the accompanying drawings:

Figure 1 is a diagrammatic elevation showing the general arrangement of cables 35 for a so called "2:1 gearless traction elevator installation."

Fig. 2 is a similar view of a so called "1:1 gearless traction elevator installation."

Fig. 3 is an enlarged side elevation of a 40 six cable equalizer as applied on a 2:1 traction elevator installation.

Fig. 4 is a side elevation thereof.

Fig. 5 is a plan view of Fig. 3.

Fig. 6 is an enlarged longitudinal section on line 6—6 Fig. 5.

Fig. 7 is an enlarged cross section on line 7—7 Fig. 5.

In the known arrangement of cables for a "2:1 gearless traction elevator installation," 50 indicated in Fig. 1 of the drawings, each car operating cable A is usually connected at one end to a "dead hitch" on a "hitch beam" and passes thence down under the sheave C on the counterweight W up to the idler 55 sheave D, then to the driving sheave E, then back to the idler sheave D, then back

to the driving sheave E, then down to an idler sheave F on the car K and thence up to the hitch plate where its other end is secured at G. This is one known 60 method of arranging the cables, and when employed therewith my equalizer will be preferably applied at the points where the ends of the cables are connected to the hitch beam. My equalizer however may be used if 65 desired at either or both hitches or ends of the cables.

In the known 1:1 gearless arrangement for traction elevator installation indicated in Fig. 2 one end of each cable A is attached 70 to the counterweight W; the cable then passes over an idler sheave D to the driving sheave E, then back to the idler sheave D, then back to the driving sheave E, and thence to the car K; the ends of the cable 75 being attached respectively to the counterweight and to the car. In this figure my equalizer is shown as applied in an inverted position on both the car and counterweight.

In Figs. 3 to 7 of the drawings I have 80 shown my invention as embodied in a six cable equalizer and will explain the invention with reference thereto.

The equalizer comprises a base plate 1 which can be readily set upon or attached 85 to the hitch plates now commonly used in connection with systems of cables indicated in Fig. 1 at either point B or G or both; and in Fig. 2 at either point B or G, or both. This base plate 1, where used for a six cable 90 equalizer is provided with six holes 1^a through which the thimble rods 5 will pass. These holes preferably are arranged as indicated in Fig. 5, which shows the upper ends of the thimble rods, and the holes in 95 the base plate are directly in line therewith. This base plate has a centrally disposed main bearing 1^b in which is journaled a main bearing pin 2^a on which are supported 100 opposite triangular yoke plates 2. The journal pin may be prevented from disengaging the bearing 1^b by any suitable means; in the drawing I have shown washers 2^d fastened to the reduced threaded ends 2^e of the pin exterior to the yokes 2 by means of nuts 2^f. 105

The yokes 2 are rigidly connected by bolts 2^b extending through spacing thimbles 2^c Fig. 6.

Pivotedly mounted on and between the yoke plates 2 are universal or gimbal-joint 110 members 3 which have lateral trunnions 3^a engaging openings in the yoke plates 2 and

pivoting the joints thereon above the pivot 2^a. These joint members 3 have trunnions 3^b at right angles to trunnions 3^a, which trunnions 3^b are pivotally engaged with 5 openings in brackets or studs 4^c formed with or attached to the under side of equalizing plates 4 in any suitable manner.

There are two equalizing plates 4 supported on the yokes by the universal or gimbal joint members 3, and these equalizing plates 4 are disposed on opposite sides of the axis 2^a on which the yokes 2 are pivoted.

Each equalizing plate 4 is provided with three openings 4^c which correspond in position with the related openings 1^a in the base plate 1 so that the thimble rods 5 can pass through openings in the base plate 1 and also through the openings in the related equalizing plates 4. The ends of said rods 5 extending through the openings 4^c in the triangles 4 are secured by any suitable means; locking and jam nuts 5^a being shown; and suitable ball and socket washers 5^b are preferably interposed between the nuts 5^a and 25 the equalizing plate 4 so as to enable the triangle plates to rock on the bolts and swing with little friction on the equalizing plates; and the top surfaces of these equalizing plates are preferably recessed to form seats 30 for the socket members of the ball and socket washers placed underneath the nuts 5^a.

It will be seen that the rocking yoke 2 will equalize strain on the two equalizing plates 4; and the joint members 3 permit 35 said equalizing plates to independently rock on the yoke.

In the example shown three ropes A are hitched to each of the equalizing plates. The ball and socket washers will allow the 40 thimble rods to oscillate or swing on the equalizing plates. The socket members of the ball and socket washers, the equalizing plates, and the base plate, may all be taper bored or have sufficiently large openings to 45 permit free swinging action of the thimble rods.

Each thimble rod 5 is connected to one of the cables A. In the example shown there are six cables and three of these cables 50 are connected to one equalizing plate 4 and the other three to the adjacent equalizing plate 4. With this arrangement it will be seen that should any cable become taut or slack, it will allow that part of the equalizing plate to which it is connected to raise 55 or lower; and in so doing will allow the other points of the equalizing plate to properly lower or raise, thereby equally distributing the load on each equalizing plate to the 60 three cables connected therewith. Naturally this may cause a movement of the other equalizing plate by the rocking of the yoke on the main bearing; but as each of the equalizing plates is arranged to swing laterally and longitudinally of the yoke, through the 65

universal joint members 3, the load will be distributed equally to all six cables. Further; if the cables connected to one equalizing plate should all come under greater or less tension than the other cables connected to the other equalizing plate, the entire equalizing plate would either lower or raise through the action of the universal joint, and the yokes rock on the main bearing, and thus, through the yoke and equalizing plates, equalize the strain on all six cables.

The equalizers may be arranged at either or both ends of the cables in the 2:1 installation as indicated in Fig. 1; in which case the equalizers will be arranged in normal 80 position as shown in Figs. 3 and 4. When the equalizers are used in the 1:1 installation they would be inverted, and attached respectively to the beam of the car, or carriage of the counterweight, as indicated in Fig. 2.

While I have illustrated the invention as applied to the cables of two known arrangements of gearless traction elevators, it will be understood that it is applicable to various other forms of cable elevators; also to other purposes in the mechanical arts where a number of cables are used and it is desirable to equalize the strains thereon; I therefore do not consider the invention restricted to use with either of the particular arrangements of cables illustrated in Figs. 1 and 2, as it can be readily adapted to other arrangements of cables in other forms of elevator construction, and also applied to other purposes in the arts where a multiple of cables are employed. And while I have shown and described a six cable equalizer it is obvious that the invention can be readily adapted for a less or a greater number of 105 cables.

What I claim is:

1. An equalizing apparatus for the purpose specified, comprising a support, a universal joint mounted on said support, an equalizing plate pivotally mounted on said joint, cables connected with the equalizing plate, at different points and universal joint washers interposed between the cable fastenings and the equalizing plates, substantially as described.

2. Means for equalizing strains on a plurality of cables and the like, comprising a support, a member pivotally mounted thereon, equalizing plates mounted upon the member and tiltable both laterally and longitudinally, and means for connecting cables with said equalizing plates, substantially as described.

3. Means for equalizing strains on a plurality of cables, etc., comprising a support, a member pivotally mounted thereon, equalizing plates mounted upon said member at opposite sides of its pivot and tiltable both laterally and longitudinally of the member,

125
130

and means for attaching cables to said equalizing plates.

4. An equalizing apparatus for the purpose specified, comprising a support, a member pivotally mounted on said support and capable of swinging longitudinally thereof, universal joints mounted on said member at opposite sides of the pivot thereof, equalizing plates mounted on said joints, and 10 cables connected with the equalizing plates, substantially as described.

5. Means for equalizing strains on a plurality of cables and the like, comprising a base, a yoke pivotally mounted thereon, 15 equalizing plates mounted upon the yoke at opposite sides of its pivot and tilttable both laterally and longitudinally of the yoke, and rods connected with said equalizing plates and extending past the yoke 20 and connecting the cables with said equalizing plates.

6. In means for equalizing strains for elevator cables and the like; the combination of a base plate having a bearing, a pair 25 of yokes pivotally mounted on such bearing, equalizing plates pivotally mounted upon said yokes at opposite sides of their pivot capable of tilting both longitudinally and laterally of the yokes, and means connecting 30 the cables with the equalizing plates, substantially as described.

7. A device for equalizing strains on a plurality of cables and the like; comprising a base plate having a main bearing, a yoke 35 pivotally mounted on said bearing, universal joint members mounted on said yoke at opposite sides of the pivot thereof, equalizing plates pivotally connected with said joint members, and a plurality of cables connected with the equalizing plates and 40 extending past the yoke and base plate.

8. The herein described equalizing device; comprising a base plate having a bearing, a yoke pivotally mounted on said bearing, a pair 45 of gimbal-joints connected with the yoke at opposite sides of the bearing, an equalizing plate pivotally connected with each gimbal-joint member, and a plurality of cables connected with the equalizing 50 plates and extending past the yoke and base plate.

9. A device for equalizing strains on a plurality of cables and the like; comprising a base plate having a main bearing, a pair 55 of yokes pivotally mounted on said bearing, universal joint members mounted on said yokes at opposite sides of the pivot thereof, equalizing plates pivotally connected with said joint members, rods connected with the 60 equalizing plates and extending past the yoke and base plate, and universal-joint washers interposed between the ends of said rods and the equalizing plates.

10. The herein described equalizer comprising a base plate having a bearing, a main

bearing pin, a pair of yoke plates pivotally mounted on said bearing pin, a pair of gimbal-joints pivoted between the yokes at opposite sides of the main bearing pin, an equalizing plate pivotally connected with each gimbal-joint, and a plurality of cables connected with each equalizing plate and extending past the yoke and base plate, substantially as and for the purpose specified. 70

11. The herein described equalizing device comprising a base plate having a main bearing, a pair of yokes pivoted on said bearing, joint members pivotally mounted on and between the yokes, a pair of equalizing plates having depending members pivotally connected with the joint members at right angles to the pivotal connections of said joint members to the yokes, cable connections extending past the plate and yokes and through the equalizing plates, and compensating ball and socket washers between the ends of the cable connections and the equalizing plates, substantially as described. 75

12. The herein described equalizing device comprising a base plate having a main bearing, a bearing pin therein, a pair of yokes mounted upon said pin, a pair of joint members pivotally mounted on and between the yokes, a pair of equalizing plates having depending members pivotally connected with 90 the joint members at right angles to the pivotal connection of said joint members to the yokes, a plurality of thimble rods extending past the plate and yokes and through the equalizing plates, retaining devices on the 100 end of said rods, and compensating ball and socket washers between the said retaining devices and the equalizing plates, substantially as described. 95

13. An equalizing apparatus for the purpose specified comprising a plate having two sets of openings, the openings in each set being arranged at the corners of triangles, a pair of yokes pivotally mounted on said base and capable of swinging longitudinally thereof, a pair of joints pivoted on said yokes at opposite sides of their pivot, equalizing plates pivoted on said joints, and members connected with the cables and extending through the openings in the base plate 110 and respectively connected with the related equalizing plates, substantially as described. 115

14. An equalizing apparatus for the purpose specified comprising a plate having two sets of openings, the openings in each set being arranged at the corners of a triangle, a yoke pivotally mounted on said base and capable of swinging longitudinally thereof, equalizing plates pivoted on said yoke at opposite sides of its pivot, each equalizing plate having three openings corresponding to the related openings in the base plate, and cable connections extending through the related openings in the base plate and connected with said equalizing plates. 120 125 130

15. An equalizing apparatus for the purpose specified, comprising a plate having two sets of openings, the openings in each set being arranged at the corners of a triangle; a pair of yoke plates pivotally mounted on said base and capable of swinging longitudinally thereof; joint-members pivoted on said yoke at opposite sides of its pivot, equalizing plates pivoted on said joint-members, each equalizing plate having openings corresponding to the related openings in the base plate, and rods extending through the related openings in the base plate and equalizing plates and connecting said equalizing plates with the cables, substantially as described.
16. A six cable equalizer comprising a base plate having a bearing and three triangularly disposed openings at opposite

sides of the bearing, a yoke mounted on said bearing, a joint-member pivoted on the yoke at opposite sides of the pivot of the yoke, an equalizing plate pivotally connected with the joint-member, the pivots of the equalizing plates on said members being at right angles to the pivots of said joint-members on the yoke, each of said equalizing plates having three triangularly arranged openings corresponding with the openings in the base plate, thimble rods extending through the related openings in the base plate and in the equalizing plates, and retaining devices on the ends of said thimble rods to keep them engaged with the equalizing plates.

In testimony that I claim the foregoing as my own, I affix my signature.

EARLE R. PIKE
